UNITED STATES PATENT OFFICE.

DAVID L. WOODS, OF MEADVILLE, PENNSYLVANIA.

POST-MOLD.

1,171,491.

Specification of Letters Patent.

Patented Feb. 15, 1916.

Application filed April 10, 1912. Serial No. 689,805.

To all whom it may concern:

Be it known that I, DAVID L. Woods, a citizen of the United States, residing at Meadville, in the county of Crawford and 5 State of Pennsylvania, have invented certain new and useful Improvements in Post-Molds, of which the following is a specification.

My invention relates to cement fence post molds, and has for its object the provision of a device adapted to mold fence posts in place, so that they do not need handling subsequent to the forming process, and also to provide a mold which does not require 15 the withdrawal of removable pins or bolts in order to extricate the molded post.

Another object of my invention is to provide a mold which will form a wire fastening means permanently on the post.

20 A further object is to provide a mold of the character described which will be cheap, durable, simple in operation, and adapted for use by those unskilled in the art of cement molding.

25 Other objects and advantages will be apparent in the course of the following description.

Figure 1 is a perspective view of my mold set up ready for use. Fig. 2 is a perspective 30 view of the completed post adapted to hold wire mesh.

Referring particularly to the drawings, the numeral A designates my mold as a whole placed upon the ground B, over a hole 35 C, and supported by removable braces or brackets D. The mold a is of smaller dimensions at the top than at the bottom.

1 designates the base or back of the mold to which are rigidly connected sides 2, to 40 one of which are connected by means of hinges 3, front sections 4 and 5. The front sections are held in place, and the mold prevented from expanding by means of clamps, comprising a fixed portion 6 encircling the 45 body portion of the mold, and a front portion 7, removably secured to the portion 6 by means of pins 8.

The sides 2 are provided with alined openings 9, through which are passed short 50 lengths of wire 10, which when the post is molded, are to serve as securing means for the fence wire.

The operation of my device is as follows: A hole of suitable size and depth is dug in

the earth at the desired place, and the mold 55 is placed over it and held in the proper position by the removable braces as shown. The lower front or cover section 5 is closed and held by the clamps, and the securing wires 10 are placed in the holes 9, cement is then 60 poured in and tamped until the lower section of the mold is filled. The upper door 4 is then closed and clamped, and the filling and tamping continued until the mold is full. After the cement is set, the clamp sec- 65 tions 7 are removed by withdrawing the pins 8, the doors 4 and 5 are opened, and the mold is removed from the post. It will be ob- 70 served that the wires 10 run through the post, and the sides 2. These wires are in- 75 tended to remain permanently in the post. Consequently it will be necessary that the holes 9 be considerably larger than the wires, in order that when the mold is removed, the wires 10 being embedded in the post will 80 pull out of the holes 9 and be against the sides of the post as shown in Fig. 2. The ends of the wires 10 are then bent into the form of a loop, and the mesh wire of the fence hooked thereto. In the case of line 85 wire fences, the wires 10 would be twisted around the line wires.

Having thus described my invention what I claim is:

A fence post mold comprising a back 85 plate, side plates rigidly secured to said back plate and having holes for the reception of short lengths of wire, a front portion made in two sections each hinged to the same side plate, clamps encircling said mold, said 90 clamps having fixed U-shaped portions encircling the body portion of the mold and removable U-shaped portions across the front of said mold and extending along the side portions until they connect with said 95 fixed portions, one of said clamps being at the bottom and one at the top of each of said front sections, said mold having braces at its corners to hold it in proper position, and said mold being of less dimensions at 100 its top than at its bottom.

In testimony whereof I hereto affix my signature in the presence of two witnesses.

DAVID L. WOODS.
